UNITED STATES PATENT OFFICE.

SAMUEL DOUGLASS, OF TEXAS, MICHIGAN.

PITMAN-COUPING.

SPECIFICATION forming part of Letters Patent No. 600,522, dated March 15, 1898.

Application filed February 1, 1897. Serial No. 621,577. (No model.)

To all whom it may concern:

Be it known that I, SAMUEL DOUGLASS, a citizen of the United States, residing in Texas, in the county of Kalamazoo and State of Michigan, have invented a certain new and useful Pitman-Coupling, of which the following is a specification.

My invention relates to improvements in pitman connections, and more particularly to improvements in pitman connections for mowing-machines and harvesters.

The objects of my invention are, first, to provide an improved pitman connection which shall not bind in any position which the various parts may assume from wear or other causes; second, to provide a pitman connection in which the joints may be kept tight; third, to provide a pitman connection in which the joint can be perfectly tight and yet be free to play from side to side to prevent binding and unnecessary strain upon the crank or wrist pin; fourth, to provide an improved joint for such purposes in which the dust can be excluded; fifth, to provide an improved ball-bearing joint for such purposes, and, sixth, to provide an improved connection between the pitman and the cutter-bar.

Further objects will appear definitely in the detailed description.

I accomplish these objects of my invention by the devices and means described in the following specification and illustrated in the accompanying drawings, in which—

Figure 1 is a side elevation, partly in section on a line corresponding to the line 1 1 of Figs. 4 and 5, of the pitman crank-wheel and cutter-bar of a mowing-machine. Fig. 2 is a detailed view of the connection between the pitman and the wrist-pin. Fig. 3 is an enlarged detail sectional elevation of the same, taken on line 3 3 of Fig. 2. Fig. 4 is an enlarged detail plan view of the connection between the pitman and the wrist-pin. Fig. 5 is an enlarged detail sectional view on line 5 5 of Fig. 1 of the connection between the pitman and cutter-bar.

In the drawings similar letters of reference refer to similar parts throughout the several views, and all of the section views are taken looking in the direction of the little arrows at the ends of the section-lines.

Referring to the lettered parts of the drawings, A is the crank-wheel of a mowing-machine.

B is the pitman, and D is the cutter-bar. 55 A' is the wrist-pin, which is secured to the crank-wheel A and on which there is a suitable flange I, that forms a cone of a ball-bearing. On this is screwed a member A'', which has on its inner end a flange I' for a 60 cone of a ball-bearing which comes opposite the flange I on the wrist-pin and forms between them a suitable ball-race for the balls F of the bearing.

The pitman-head B' is made spherical on the 65 exterior, except at the sides and the point of attachment to the pitman. The opening in the head is also spherical, except where it opens at the sides and exactly fits over the balls F and retains them in the ball-race on 70 the wrist-pin. The wrist-pin A and the member A'' have cup-shaped flanges a a', fitted onto the exterior of the pitman-head and are cupped to fit the same to exclude sand and dust so far as possible. The opening through 75 the head is larger than the wrist-pin to permit of a considerable play of the wrist-pin and pitman to prevent binding. The spherical opening of the head holds the joint tight.

The member A'' being adjustable retains 80 the balls tight in the bearing and so takes up all play and lost motion no matter what position the pitman takes within the limits of its motion. The flange a' serves as a convenient means to handle the member A'', and 85 it is locked in position by a suitable nut.

On the cutter-bar D is an upwardly-projecting arm D', which takes the place of the usual eye or journal at that point. This arm is curved in the arc of a true circle, the periphery of which is toward the end of the bar. The connection to the bar consists of the head C, which is recessed to extend each side of the arm D' and contains a roller E' on a pivot 90 n therethrough. The roller fits the inside of 95 the arm D'. Within the head C is a block C', adjustable therein. The outer side of the block is recessed to correspond to the outer surface of the arm D'. Between the block C' and the arm D' are rollers E to reduce the 100 friction. The head is channeled out between block C' and arm D' to retain the rollers E in

place. The block C' fits on a suitable journal and against a shoulder on the end of the pitman B.

The pitman B is secured to the heads B' 5 and C by screw-threads, both of which are either right-handed or left-handed. By screwing the pitman into head C the block C' is adjusted and the bearing kept tight. This does not vary the length of the pitman, as it is 10 screwed out of the head B' as fast as it is screwed into the head C, and vice versa.

Having thus described my improved pitman-coupling, I desire to state that it can be greatly varied in its details without departing 15 from my invention.

I desire to state that the crank connection will be very effective without the flanges a a', and I am also aware that the cones can be adjusted and secured in other ways.

20 When the crank connection is used in such positions that the protection from dust and sand is not required and the flanges a a' are dispensed with, the form of the exterior of the head is not material.

25 The roll E' in the connection to the cutter-bar might be dispensed with, though it serves a useful purpose, and the number of rolls E is not material.

Other changes will readily suggest themselves to those skilled in the art to which my 30 invention appertains.

Having thus described my invention, what I claim as new, and desire to secure by Letters Patent, is—

35 1. In a pitman-coupling the combination of the crank-wheel A; the wrist-pin A', thereon having the conical flange I; a member A'', adjustable thereon having conical flange I', opposite the flange I, a pitman-head B', having an opening therethrough for the wrist-pin that is spherical or globular on its inner surface; and bearing-balls F, retained between the conical flanges and the head as 40 specified.

45 2. In a pitman-coupling the combination of a wrist-pin with a suitable ball-race therein; suitable bearing-balls in said race; a pitman-head having an opening larger than the

wrist-pin to permit of play and spherical or globular on its inner surface to contact with 50 the bearing-balls.

3. In a pitman-coupling the combination of the crank-wheel A, the wrist-pin A', thereon having the conical flanges I, and cup-flanges a, thereon; a member A'', adjustable 55 thereon having conical flanges I', opposite the flange I, and cup-flange a'; a pitman-head B', spherical in form having an opening therethrough for the wrist-pin that is spherical on its inner surface; and bearing-balls 60 F, retained between the conical flanges and the head as specified.

4. In a pitman-coupling the combination of an inner member containing a ball-race; bearing-balls in said race; and an outer member 65 having its inner surface spherical or globular in form to contact with said balls.

5. In a pitman-coupling the combination of an arm D', curved in an arc of a true circle; a pitman-head recessed to embrace the 70 same; a pivot n, through said head with a roller E', thereon to engage said arm; a block C', adjustable in said head and recessed out to correspond to the exterior of said arm D'; bearing-rollers E, between said block and 75 arm; and the pitman B, with a screw connection to said head to adjust said block C', as specified.

6. In a pitman-coupling the combination of an arm D', curved in the arc of a true circle, a pitman-head recessed to embrace the 80 same; a pivot n, between the head and said arm; a block C', adjustable in said head and recessed out to correspond to the exterior of the arm D'; bearing-rollers E, between said 85 blocks and arm; and the pitman B, with a screw connection in said head to adjust said block C', as specified.

In witness whereof I have hereunto set my hand and seal in the presence of two witnesses. 90

SAMUEL DOUGLASS. [L. S.]
